UNITED STATES PATENT OFFICE.

MAURICE L. ROSS AND BERNIE A. ROSS, OF CHICAGO, ILLINOIS, ASSIGNEES TO HERTZ
DRIV-UR-SELF STATIONS, INC., OF CHICAGO, ILLINOIS, A CORPORATION OF DELA-
WARE.

KEY CARRIER.

Application filed August 27, 1926. Serial No. 131,864.

Our invention relates to key carriers, and the same has for its main object the provision of an improved construction of this character which will embody certain desired features of simplicity, efficiency and convenience, and with which is novelly combined a holder device carrying an address plate for identifying the owner of the key carrier, the arrangement being such that the address plate is readily removable and replaceable so that when the owner of the key carrier removes from one address to another, the address plate can be conveniently changed.

15 Other objects will appear hereinafter.

The invention consists in the combinations and arrangements of parts hereinafter described and claimed.

The invention will be best understood by reference to the accompanying drawing forming a part of this specification, and in which,

Fig. 1 represents a plan view of our improved key carrier;

Fig. 2 represents an edge view thereof;

Fig. 3 is a sectional view, on an enlarged scale, taken substantially on the line 3—3 of Fig. 1, this view showing the type of chain employed for carrying the keys and also showing the terminal fastener for the chain;

Fig. 4 is a longitudinal section taken on the line 4—4 of Fig. 1;

Fig. 5 represents a plan view of the main holder and guide, the chain and address plate holder being omitted;

Fig. 6 is a plan view of an address plate;

Fig. 7 is a plan view of the address plate holder; and

Fig. 8 represents a cross section on an enlarged scale taken on the line 8—8 of Fig. 1.

Our invention, in its preferred form of construction as illustrated in the accompanying drawing, comprises a main holder 9 made in the form of a flat faced key having an elongated shank portion 10 and a circular head portion 11. A guide strip 12 is secured as by means of rivets 13 upon one face of the main holder and extends the entire length thereof from the free end of the shank portion 10 to the opposite free end of the head portion 11 as best shown in Fig. 5. The longitudinal marginal edges of the guide strip 12 are offset outwardly from the face of the main holder so as to produce guiding edges or flanges 14 on which our

address plate and address plate holder are slidably mounted.

The address plate holder of the present invention comprises a channel shaped frame consisting of a face plate 15, which is made of celluloid or other suitable transparent material, connecting opposed sides 16 whose marginal edges are bent inwardly toward each other to provide flanges 17 adapted slidably to engage the under faces of the guiding edges 14, whereby to mount and retain the address plate holder upon the guide strip. 18 designates an address plate which may be produced from cardboard, paper or other suitable inexpensive material, and on which is printed, written or otherwise inscribed the name and address of the owner of the key carrier. The address card is placed within the address card holder, against the underside of the face plate 15, and between the sides 16 as best shown in Fig. 8, so that when the inturned flanges 17 are applied to the guiding edges 14 the address plate 18 will seat upon the top surfaces of the guiding edges 14 and will be imprisoned between said guiding edges 14 and the transparent face plate 15. In the present exemplification, we have shown the guide strip 12 formed with a stop piece 19 at the end corresponding with the free end 75 of the handle portion 10; and in view of the provision of this stop, it will be evident that the address plate holder with its address plate is applied to the guide strip from the head end 11, the address plate holder with 80 its address plate being slidably moved upon the guiding edges 14 until they abut the stop 19.

According to a feature of our present invention, the head end 11, guide strip 12, address plate 18, and face plate 15 are provided with the respective apertures 20, 21, 22 and 23, said apertures being provided in corresponding ends of said parts and being of corresponding size, as clearly illustrated 85 in Figs. 4 to 7 inclusive. The means for carrying the keys as shown in the present exemplification consists of a chain 24 adapted to be taken through the registering apertures 20, 21, 22 and 23; said chain being made of 90 hollow ball-like links 25 connected by single strands 26, the terminals of the single strands 26 being headed as at 27 inside the ball-like links as best shown in Fig. 3. As 95 a means for connecting the terminal ends 100 105 110

of the chain, we preferably employ a fastener 28 of hollow cylindrical form, there being end openings 29 for receiving the link strands 26 and a center opening 30 for receiving the ball-like links 25, it being observed that the center opening 30 is in communication with the end openings 29 by slits or narrow necks 31 through which the strands 26 are slipped when the ball-like links are entered into or removed from the center opening 30. By means of this fastener, either of the terminal ends of the chain may be disconnected for the removal or application of keys. It will be evident that the address plate and the address plate holder will be held in place upon the guide strip when the chain 24 is passed through the apertures thereof.

From the foregoing description and a study of the drawing, it will be apparent that we have provided a simple, efficient and convenient key carrier and one in which the address plate can be quickly and conveniently replaced from time to time as occasion requires and without expense.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

1. A key carrier comprising a main hold-

er provided with a guide strip and an aperture; a holder with an address plate mounted to slide on the guide strip and provided with an aperture adapted to register with the first named aperture; and key carrying means extending through the aperture of the main holder and the aperture of the address plate holder, substantially as described.

2. A main holder provided with guide strips; an address plate holder consisting of side flanges connected by a transparent face plate arranged on the main holder with side flanges engaging said guide strips; an address plate contained in the address plate holder and visible through the face plate thereof; aligned apertures in one end of the main holder and face plate; and key carrying means extending through said apertures, substantially as described.

3. A main holder in the form of a key having a shank and head, there being an aperture in said head; a strip with guide edges secured to said holder and extending the entire length of the shank and head, in combination with an address plate holder consisting of side flanges and a connecting transparent face plate, said side flanges having sliding engagement with said guide edges and said face plate having an aperture registering with the aperture in said head; an address plate contained in the address plate holder and displayed through the face plate thereof; and key carrying means extending through said apertured head and face plate, substantially as described.

In testimony whereof we have signed our names to this specification.

MAURICE L. ROSS.
BERNIE A. ROSS.
